(57) **CLAIM**

The ornamental design for a beach shade, as shown and described.

DESCRIPTION

FIG. 1 is a three-dimensional view of the top, rear, and right sides of my newly designed beach shade;

FIG. 2 is a bottom up and front side stereo view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of section 9 shown in FIG. 1 thereof;

FIG. 10 is an enlarged view of section 10 shown in FIG. 1 thereof;

FIG. 11 is an enlarged view of section 11 shown in FIG. 1 thereof;

FIG. 12 is an enlarged view of section 12 shown in FIG. 1 thereof;

FIG. 13 is an enlarged view of section 13 shown in FIG. 1 thereof;

FIG. 14 is an enlarged view of section 14 shown in FIG. 1 thereof;

FIG. 15 is an enlarged view of section 15 shown in FIG. 2 thereof; and,

FIG. 16 is an enlarged view of section 16 shown in FIG. 2 of the beach shade.

The broken lines shown in the drawings illustrate portions of the beach shade that form no part of the claimed design.

1 Claim, 16 Drawing Sheets
